UNITED STATES PATENT OFFICE.

HARRY W. BOLENS, OF PORT WASHINGTON, WISCONSIN.

SEAT-SPIDER.

No. 824,232.

Specification of Letters Patent.

Patented June 26, 1906.

Application filed April 24, 1903. Serial No. 154,107.

To all whom it may concern:

Be it known that I, HARRY W. BOLENS, a citizen of the United States, and a resident of Port Washington, in the county of Ozaukee and State of Wisconsin, have invented certain new and useful Improvements in Seat-Spiders; and I do hereby declare that the following is a full, clear, and exact description thereof.

My invention consists in certain peculiarities of construction and combination of parts hereinafter particularly set forth, with reference to the accompanying drawings, and subsequently claimed, its object being to provide simple, economical, light, strong, and durable spiders for the chair and stool trade, each spider being of the species in which primarily independent parallel metal arms attachable at their ends to a chair or stool seat are combined with a suitable spreader that may be of cast metal or otherwise, as found preferable in practice, the one herein shown being of the cast-metal variety.

Figure 1 of the drawings represents a side elevation of a tilt-seat spider made in accordance with my invention; Fig. 2, a plan view of same, partly in horizontal section; Fig. 3, a transverse sectional view of the spider, this view being indicated by lines 3 3 in the second figure; Fig. 4, a partly sectional detail view illustrating a reversal of what is shown in the above-described figures; Fig. 5, a perspective view of a fragment of a spider-arm that is made three-ply in a vertical direction, and Fig. 6 a similar view showing that the vertical portion of each spider-arm may be corrugated in the direction of its width and length.

Referring by letter to the drawings, A indicates each of the primarily independent parallel arms, and B the spreader of an improved chair or stool seat spider. Each spider-arm is of rolled metal, for the most part angular in the form of a T, inverted or otherwise. The vertical portion of each spider-arm is of less length than the horizontal portion, and said arm is elevated at its ends, these ends being apertured for the engagement of fastening devices by which the spider is made fast to a chair or stool seat.

The horizontal portion of each spider-arm rests flat on the spreader B, and this spreader is shown provided with lips b, that overlap the spider-arms. Rivets c are shown extending through openings provided in the spreader,

and these rivets engage notches with which edges of the horizontal portions of the spider-arms are provided, heads of the rivets being in lapping contact with said arms. The rivets hold the spider-arms in snug engagement 60 with the recesses under the spreader-lips b herein shown; but it is to be understood that other rivets may be substituted for said lips, in which case said spider-arms will be held on the spreader by vertical rivets only. By 65 notching the spider-arms to engage the rivets said arms are not weakened, as would be the case if they were punched out to form rivet-holes.

The general outlines of the spreader B may 70 be indefinitely varied from what is herein shown, and the vertical portions of the spider-arms may extend up or down, according to the way said spreader is made in practice to suit the demands of the trade, the spider-arm illustrated in Fig. 4 being the reverse of those shown in the other figures. For tilt-seat spiders the spreader is provided with depending pivot-ears d and lugs e for the support of spiral tension-springs, as is customary in the art, and while said spreader is herein shown as being a casting it may be sheet metal of suitable strength.

Each spider-arm is herein shown in most instances as having two-ply horizontal and 85 vertical portions, although made from a single piece of metal; but, as shown in Fig. 5, its vertical portion may be made three-ply by employing sufficient metal and properly folding the same. It is also to be understood 90 that ordinary commercial T-iron of sufficient strength may be found suitable for the spider-arms.

As shown in Fig. 6, each spider-arm may be stiffened by corrugating its vertical portion, and the corrugations may be in the direction of the width or length, or both, of said vertical portion of the arm.

It is preferable, as herein shown, to have the vertical or stem portion of each spider-arm of a depth greater than the width of the horizontal portion of said arm from the center of the same in either direction, whereby greater rigidity is obtained.

Having thus described my invention, what 105 I claim as new, and desire to secure by Letters Patent, is—

1. A seat-spider comprising primarily-independent parallel-rolled metal T-arms, a spreader supporting the arms, spreader-lips 110

lapping horizontal portions of the arms, and rivets engaging the spreader and edge notches of the spider-arms to hold the latter in snug engagement with recesses under the spreader-
5 lips.

2. A seat-spider comprising a spreader, parallel primarily-independent **T**-arms the horizontal portions of which rest flat upon the spreader, and fastening devices in connection with said spreader opposing the edges of said horizontal portions of said arms.
10

3. A seat-spider comprising a spreader, parallel primarily-independent **T**-arms having the vertical portions of each of less length
15 than the horizontal portion thereof that rests flat upon the spreader, and fastening devices in connection with said spreader in opposi-

tion to the edges of said horizontal portions of said arms.

4. A seat-spider comprising a spreader, 20 parallel primarily-independent **T**-arms the horizontal portions of which rest flat upon the spreader, and rivets that engage the spreader, oppose edges of said horizontal portions of the arms and are headed on the same. 25

In testimony that I claim the foregoing I have hereunto set my hand, at Milwaukee, in the county of Milwaukee and State of Wisconsin, in the presence of two witnesses.

HARRY W. BOLENS.
